UNITED STATES PATENT OFFICE.

LEE W. LAMBOY, OF CHICAGO, ILLINOIS. ASSIGNOR TO SEFTON MANUFACTURING CORPORATION, OF CHICAGO, ILLINOIS, A CORPORATION OF NEW YORK.

CHICK BOX.

Application filed November 23, 1925. Serial No. 70,781.

My invention relates to boxes adapted for shipment of chicks and more particularly to novel means for spacing the boxes apart when stacked on each other to afford proper 5 ventilation for the chicks through the ventilated openings formed at the top of the box.

Heretofore various means have been employed for accomplishing this object but 10 such prior devices have been ineffectual in some respects and expensive and difficult to make. The most common practice is to secure wooden slats to the tops of the boxes but these slats add considerable weight to 15 the boxes and are difficult to secure in position.

The principal object of my invention is to provide triangular strips preferably formed of corrugated board or the like and formed 20 of one piece so bent as to provide a hollow spacer substantially triangular in cross section, one face of the spacer being adapted to be glued to the bottom of the box.

Another object of my invention is to 25 maintain the shape of the spacer by means of strips of adhesive tape wrapped around the spacer.

The above and incidental objects of my 30 invention will become apparent from the following description taken in connection with the drawings.

In said drawing, Figure 1 is a perspective view of two chick boxes having spacers embodying my invention applied thereto; Fig. 35 2 is an enlarged perspective view of a spacer embodying my invention; and Fig. 3 is a fragmentary cross-sectional view taken through the sheet of material from which the spacer is formed, the view illustrating 40 that the preferred material is corrugated paper board, though other suitable material may be used, if desired.

In Fig. 1, I have illustrated two chick 45 boxes one mounted on the other. As is usual the lids, as well as the sides, of the boxes are provided with rows of ventilating holes 6. In shipment the boxes are stacked or piled upon each other and it is essential 50 that the boxes be spaced apart so that the ventilating holes in the lids are not covered, the holes being employed to furnish air to the chicks being shipped. I space the boxes apart by means of spacers 7, the construction of which is best illustrated in Fig. 2. 55 Each spacer is formed of a strip of corrugated board or other suitable material. The strip is scored lengthwise to provide four sections or panels 8, 9, 10 and 11. Sections 8, 9 and 10 are preferably of substantially the same width and section 11 is slightly 60 narrower. The strip is folded as shown in Fig. 2 so that the two outermost sections 8 and 11 overlap. In order to hold or maintain the shape of the spacer strips of adhesive tape 12, which may be formed of paper 65 or other suitable material are wrapped around the spacer.

After the spacers are so formed, the upper face of the outer section 11 is smeared with glue or any suitable adhesive material and 70 then pressed against the bottom of the box, the spacer thus being rigidly secured to the box. I preferably employ two spacers for each box and so position them that when the box is piled on another box the spacers 75 are between the rows of ventilating holes in the lid of the lower box. The spacers not only space apart the boxes but also materially strengthen the bottom of the boxes. By overlapping the end sections 8 and 11 of 80 each spacer to form a double wall at the top I also materially increase the strength of the spacer and make it easier to form the spacer.

Having thus described my invention, what 85 I claim is:

1. A box of the class described comprising a bottom and side walls, a cover, and a plurality of supports mounted upon said box, each of said supports comprising a single 90 strip of material folded to form a triangular hollow shape and having means for holding and maintaining said strip in triangular form.

2. In a box of the class described having 95 ventilating openings in the top thereof, a plurality of triangularly shaped members separate from but secured to the box and extending entirely across the box, each of said members being comprised of a single 100 strip scored to form a plurality of sections and being so folded that one of the outer sections is superimposed on the other outer section, and means independent of said box for holding and maintaining said sections 105 in triangular shape and superimposed relation.

3. In a box of the class described comprising bottom and side walls and a cover having 110 ventilating perforations and a plurality

of supports mounted on said box, each of
said supports comprising a single separate
strip of material folded into triangular
shape, means for maintaining the triangular
shape of each support, and means for se-
curing one face or side of each support flat
against the box.

4. In a box of the class described com-
prising bottom and side walls and a cover
10 having ventilating perforations, and a plu-
rality of supports mounted on said box, each
of said supports comprising a single sepa-

rate strip of material scored longitudinally
to form four sections, and bent on the scored
lines so that the two outer sections overlap
11 and form a double wall of the triangular
shaped support while the remaining inner
sections form the other sides thereof, and
tape around the support to maintain its tri-
angular shape, and glue for securing the 20
double sides of the supports to the box.

In testimony whereof, I have subscribed
my name.

LEE W. LAMBOY.
